METHOD OF GRINDING BUTT JOINTS OF WOUND CORES

John H. Bramble, Sharpsville, and Michael Dunn, Sharon, Pa., assignors to Westinghouse Electric & Manufacturing Company, East Pittsburgh, Pa., a corporation of Pennsylvania

Application April 15, 1941, Serial No. 388,630

9 Claims. (Cl. 51—135)

This invention relates to the working of the faces of sheet steel laminations that are bonded together and cut to form butt joints in a magnetic structure of induction apparatus, such as transformers. Recent developments in magnetic steel have produced steels having very good magnetic properties of low loss and high permeability in the direction in which the material is rolled during its process of manufacture. To obtain the maximum benefits from the use of such material, it is necessary to use it in such manner that the lines of magnetic flux, that is the direction of magnetization, coincides substantially with the direction of rolling the material during its process of manufacture.

Core structures have been developed in which the direction of magnetization coincides throughout with the direction of rolling by forming the core loops of a continuous strip or ribbon or steel slit to the proper width and wound to a predetermined thickness of the material on a mandrel of such shape as to give the desired window opening.

The core loops so formed are annealed to relieve strains in the material caused by the winding operation and are then impregnated with bonding material and baked to bond the several layers of magnetic material solidly together. In order to provide for assembling the wound core loop structure about form-wound copper coils of the electric circuit, the core loops are cut to form two U-shaped parts and the butt joint surfaces formed by this cut are worked by grinding and etching to provide a flat surface free from short circuiting burrs.

It has been found that for grinding the butt joint surfaces on this type of core structure, a water cooled abrasive belt grinder consisting of a continuous belt produces the best surface in the shortest grinding time. It had been the practice when grinding the surfaces on this type of grinder to rest the core parts against a bridge type of stop so that the planes of the laminations being ground were parallel to the direction of movement of the abrasive belt. It was soon found, however, that this method of grinding was critically related to the straightness or flatness of the cut surface before grinding. The belt life was found to be good only when extremely close tolerances were maintained during the cutting or sawing operation. It was also found that the core parts could stand only a very limited amount of grinding in a direction parallel to the planes of the laminations without producing thick burrs that become difficult to etch, and also that this

method of grinding tended to separate the laminations one from the other, that is, to split or destroy the bond between the laminations.

It has been found that when the joint is ground by movement of the abrasive surface of the belt across the several laminations, that is, so that the belt moves from one lamination to the next or at right angles to the planes of the laminations as they contact the belt instead of parallel to the edges of the laminations contacting the belt, a flatter ground surface is produced and the burrs are much more readily removed by etching. When the grinding is done by movement of the abrasive surface across the laminations instead of in the direction of the laminations, the resulting burrs from each lamination are all on the same side of the several laminations, there being a burr on one side only of each lamination instead of on both sides as when the grinding surface passes along the edge of the lamination.

It is an object of the invention to provide for grinding the surfaces on the opposite sides of a butt joint in a laminated sheet steel core structure, the several laminations of which are bonded together to provide a smooth flat joint surface.

It is a more specific object of the invention to provide for grinding such joint surfaces with a high speed grinding surface traveling in a direction across the laminations so as not to split the several bonded laminations and separate them from one another, and so as to provide a flatter surface, and one from which the removal of the burrs is more readily facilitated.

Other objects and advantages of the invention will be apparent from the following description of one embodiment thereof, reference being had to the accompanying drawing, in which:

Figure 1 is a side elevational view partly in section of apparatus arranged for grinding the laminated core parts.

Fig. 2 is a perspective view of a portion of the apparatus shown in Fig. 1.

Fig. 3 is a top plan view of the parts of the apparatus shown in Fig. 2, and

Fig. 4 is an enlarged elevational view of the ends of the laminations at the joint surface showing the burrs formed by grinding.

Referring to the drawing, a tank 1 is provided for collecting water from an endless abrasive belt 3 which travels over the rolls 4 and 5 the upper flat portion of which travels over a flat table 2 positioned under the smooth side of the abrasive belt and which may be supported from the side walls of the tank 1 by brackets 9. A U-

shaped laminated core structure 11 which constitutes a part of a complete magnetic loop structure is shown in position for grinding. The structure 11 comprises a plurality of layers 12 of sheet steel magnetic material positioned one layer upon the other so that each layer extends about the space between two parallel legs 13 and 14, the ends of which are cut and ground to form the surfaces of a butt joint when two similar core parts 11 are positioned together to form a complete magnetic loop. Two bridge type stops are provided for engaging the two legs of the core part being ground over a narrow surface closely adjacent to the traveling belt 3. One stop 15 is rigidly fixed, as by handwheel operated screws 16, to the table top 8 and the core part 11 is positioned to straddle this bridge rest so that it will rigidly bear against the first of the two legs 13 to be engaged by the traveling belt 3, which is indicated by the arrow, as moving from the left toward the right in the several views. The second bridge rest stop 17 is yieldably mounted with respect to a bracket 18 that is attached to the table top 8 by handwheel operated screws 19 and into recesses in which spring members 20 are provided so as to permit a certain amount of yieldable motion of the member 17. A supply of water is provided through pipe 21, the lower part having two branch horizontal end portions 22 and 23 from the underside of which water is supplied to the surface of the abrasive belt 3. The portion 23 extends along a recess 24 in the rest 15. A motor 25 or other suitable driving means is provided and connected through any suitable driving mechanism to rotate the rolls 4 and 5 and carry the belt 3 in a clockwise direction so that the portions engaging the surfaces being ground traverse from left to right, as viewed in the drawing. The belt traverses at a very high speed such as 700 feet per minute and carries water for cooling the belt and aiding in the grinding operation from the lower part of the tank 1 to the first leg 13 to be ground, the water supplied through the pipe 23 maintaining the abrasive belt moist as it passes under the second leg 14 of the core structure.

It has been found that in providing the two bridge rests 15 and 17, the first of which is rigid and the second of which yieldably engages the leg 14 that a certain amount of spring in the core part being ground may take place without injuring the structure whereas if both legs of the core structure are rigidly braced against bridge stops, a certain chattering or jumping of the core part being ground takes place which interferes with the production of a continuous flat, smooth surface. By using the two bridges 15 and 17, one of which is rigidly fixed against movement and the other of which is yieldably mounted, a firm support of both legs of the core part is provided and a continuous quiet grinding operation takes place producing a very flat surface.

As shown in Fig. 4, the layers 12 of magnetic material are spaced apart slightly by bonding material in the spaces 26 and the burrs 27 that are formed by the action of the abrasive belt 3 appear only on one side of each of the lower surfaces of the laminations 12 which are thinner and thus more readily removed than when the belt travels in the direction along the surface of the laminations instead of across them. The amount of material that must then be removed by etching is small and the time required for the etching operation is correspondingly reduced.

Since the shortest dimension of the surface being ground is parallel to the direction of grind-

ing, less heat is evolved on the surface being ground and the life of the belt is much greater than when the structure is ground by movement of the belt parallel to the edges of the lamination.

5 Modifications in the apparatus and in the details of the method of grinding disclosed may be made within the spirit of the invention and we do not wish to be limited otherwise than by the scope of the appended claims.

10 We claim as our invention:

1. Apparatus for working the outer end surfaces of U-shaped core portions formed of a plurality of laminations of magnetic sheet steel positioned flatwise and bonded together, the one upon the other about the space between the two legs of the U-shaped core portion, comprising means for positioning the U-shaped core portion in engagement with a movable flat grinding surface with the ends of the laminations in engagement with the grinding surface substantially at right angles to the direction of motion of the grinding surface and including means for supporting the core portion comprising a pair of narrow low fixed bridge rests, closely adjacent to the grinding surface, the bridge rest for supporting one leg of the core portion being rigidly fixed in position to prevent movement of the supported leg with the grinding surface, and the bridge rest for supporting the other leg of the core portion being yieldably biased against the other core leg.

2. Apparatus for working the outer end surfaces of U-shaped core portions formed of a plurality of laminations of magnetic sheet steel positioned flatwise and bonded together, the one upon the other about the space between the two legs of the U-shaped core portion, comprising means for positioning the U-shaped core portion in engagement with a movable flat grinding surface with the ends of the laminations in engagement with the grinding surface substantially at right angles to the direction of motion of the grinding surface and including means for supporting the core portion comprising a pair of narrow low fixed bridge rests, one of said rests exerting a rigid resistance against movement of one core leg and the other bridge rest exerting a yielding resistance against movement of the other core leg.

3. The method of working the end surfaces of 50 a multiple leg core part formed of a plurality of layers of magnetic sheet steel positioned at right angles to a plane through the axis of the core legs and bonded together to provide flat surfaces for cooperating with similar surfaces to form a 55 butt joint, comprising positioning the ends of the core legs to be worked in engagement with an abrasive surface moving in a plane and in rigidly supporting the first leg to be engaged by said abrasive surface against movement with the surface and in yieldingly supporting the remaining portion of the core part against movement with the surface.

4. The method of working the end surfaces of 60 a U-shaped core part formed of a plurality of layers of magnetic sheet steel positioned at right angles to a plane through the axis of the core legs and bonded together to provide flat surfaces for cooperating with similar surfaces to form a 65 butt joint, comprising positioning the ends of the core legs to be worked in engagement with an abrasive surface moving in a plane and in rigidly supporting the first leg to be engaged by said 70 abrasive surface against movement with the surface and in yieldingly supporting the other leg 75 of the core part against movement with the sur-

face to thus eliminate chatter and produce a smooth flat surface.

5. Apparatus for working the surfaces of magnetic core structures formed of U-shaped core parts having a plurality of layers of magnetic sheet steel positioned at right angles to a plane including the axes of the two end portions thereof comprising a flat table top surface, an endless abrasive belt and means for moving the abrasive belt across the table top to provide a continuously moving flat abrasive surface, bridge rests for supporting the end portions of the U-shaped core part when brought into engagement with the abrasive surface including a fixed rest for rigidly engaging one of said end portions adjacent the abrasive surface, and a rest for yieldingly engaging the other of said end portions.

6. Apparatus for working the surfaces of magnetic core structures formed of U-shaped core parts having a plurality of layers of magnetic sheet steel positioned at right angles to a plane passing through the axes of the two leg portions thereof comprising a flat table top surface, an endless abrasive belt and means for moving the abrasive belt across the table top to provide a continuously moving flat abrasive surface, bridge rests for supporting the end portions of the U-shaped core part when brought into engagement with the abrasive surface including a narrow rest positioned close to the abrasive surface between the end portions of the core and fixedly mounted to rigidly support the first of the two leg portions against movement with the abrasive belt, and a narrow rest positioned close to the abrasive surface and mounted to yieldingly support the other of said leg portions.

7. Apparatus for working the surfaces of magnetic structures formed of U-shaped core parts having a plurality of layers of magnetic sheet steel positioned at right angles to a plane passing through the axes of each of the two leg portions thereof comprising a flat table top surface, an endless abrasive belt and means for moving the abrasive belt across the table top to provide a continuously moving flat abrasive surface, bridge 45 rests for supporting the end portions of the

U-shaped core part when brought into engagement with the abrasive surface including a narrow rest positioned close to the abrasive surface between the end portions of the core and fixedly mounted to rigidly support the first of the two leg portions against movement with the abrasive belt and a narrow rest positioned close to the abrasive surface and flexibly mounted to yieldingly support the other of said leg portions, and means for supplying water to the abrasive surface adjacent the two leg portions of the core part.

10 15 20 25 30 35 40 45

8. The method of working the outer end surfaces of core parts having a plurality of core leg portions formed of a plurality of laminations of magnetic sheet steel positioned flatwise and bonded together, the one upon the other comprising positioning the leg portions of the core parts in engagement with a movable flat grinding surface with the ends of the laminations in engagement with the grinding surface substantially at right angles to the direction of motion of the grinding surface and in rigidly supporting one leg portion of the core closely adjacent to the grinding surface to prevent movement of the supported leg portion with the grinding surface and in yieldably supporting the other leg portions of the core part to prevent movement of the supporting leg portion with the grinding surface.

9. The method of working the outer end surfaces of core parts having a plurality of core leg portions formed of a plurality of laminations of magnetic sheet steel positioned flatwise and bonded together, the one upon the other comprising positioning the leg portions of the core parts in engagement with a movable flat grinding surface with the ends of the laminations in engagement with the grinding surface substantially at right angles to the direction of motion of the grinding surface and in supporting the core portion by exerting a rigid resistance against movement of one core leg portion and exerting a yielding resistance against movement of the other core leg portion.
